JEWISH MEMORIAL YAHRZEIT CANDLE HOLDER

Joseph Edmund Schwarz, West Quaddy Head,
Box 84, R.F.D. 2, Lubec, Maine 04652

Filed Nov. 10, 1972, Ser. No. 305,269

Term of patent 14 years

Int. Cl. D26—01

U.S. Cl. D48—2

FIG. 1

FIG. 2

FIG. 3

FIG. 1 is a front elevational view of Jewish memorial candle holder showing my new design.

FIG. 2 is a top plan view thereof.

FIG. 3 is a rear elevational view thereof.

The undisclosed sides of the base are substantially identical to the rear of the base. The broken lines are shown in FIG. 1 for illustrative purposes only.

I claim:

The ornamental design for a Jewish memorial Yahrzeit candle holder, as shown and described.
